CLAIM

(57) The ornamental design for a bed frame, as shown and described.

DESCRIPTION

FIG. 1 is a rear perspective view of a bed frame, showing my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The broken lines in FIGS. 1-9 illustrate portions of the bed frame which form no part of the claimed design. The broken lines in FIGS. 1 and 9 depict boundary lines of the enlargement that form no part of the claimed design.

1 Claim, 9 Drawing Sheets
